Primary Examiner — Leanne Was-Englehart*Assistant Examiner* — Justin A Johnson*(74) Attorney, Agent, or Firm* — Billion & Armitage(57) **CLAIM**

We claim the ornamental design for a skydiving helmet, as shown and described.

DESCRIPTIONFIG. 1 is a perspective view of a skydiving helmet;
FIG. 2 is a front elevation view of the skydiving helmet shown in FIG. 1;
FIG. 3 is a rear elevation view of the skydiving helmet shown in FIG. 1;
FIG. 4 is left-side elevation view of the skydiving helmet shown in FIG. 1;
FIG. 5 is right-side elevation view of the skydiving helmet shown in FIG. 1;
FIG. 6 is a top plan view of the skydiving helmet shown in FIG. 1; and,
FIG. 7 is a bottom plan view of the skydiving helmet shown in FIG. 1.
The broken lines illustrate portions of the skydiving helmet and form no part of the claimed design.**1 Claim, 7 Drawing Sheets**(56)
